[57] CLAIM

The ornamental design for a sensor for solar and wind energy monitor, as shown and described.

DESCRIPTION

FIG. 1 is a view in perspective of the sensor for solar and wind energy monitor showing my new design; FIG. 2 is a front view in elevation thereof with portions broken away for ease of illustration;

FIG. 3 is a side view with portions broken away for ease of illustration, with the opposite side view being a mirror image thereof;

FIG. 4 is a top plan view thereof; and,

FIG. 5 is a bottom plan view thereof.
